UNITED STATES PATENT OFFICE.

LEWIS J. HEINTZ, OF BUFFALO, NEW YORK.

DESIGN FOR A FINGER-RING.

SPECIFICATION forming part of Design No. 24,160, dated April 2, 1895.

Application filed January 15, 1895. Serial No. 535,038. Term of patent 3½ years.

To all whom it may concern:

Be it known that I, LEWIS J. HEINTZ, a citizen of the United States, residing in the city of Buffalo, in the county of Erie and State 5 of New York, have invented and produced a new and original Design for a Finger-Ring, of which the following is a specification, reference being had to the accompanying drawings, showing a part thereof.

10 Figure 1, represents a top view showing my design for a finger ring, and Fig. 2, represents a side elevation of the same, these two views being deemed necessary to fully illustrate my design.

15 The leading feature of my design consists

in the circular ornamental portion 1, secured to the band portion 3, of the ring at the points 4 and 5. A series of precious stones or enamel devices is mounted in the upper face of the circular ornamental portion 1. It will be noticed that there is a clear central opening 6, within the ornamental portion 1. 20

I claim as my invention—

The design for a finger ring, substantially as herein shown and described.

LEWIS J. HEINTZ.
